INVENTOR:

Luther C. Johnston.

UNITED STATES PATENT OFFICE

LUTHER C. JOHNSTON, OF MORGANTON, NORTH CAROLINA, ASSIGNOR OF ONE-FOURTH
TO J. E. GARRISON AND ONE-FOURTH TO JOE KJELLANDER, BOTH OF BURKE
COUNTY, NORTH CAROLINA

SELF-LATHERING SAFETY RAZOR

Application filed July 30, 1927. Serial No. 209,464.

This invention relates to razors, and more particularly to so-called safety razors.

The object of the invention is to provide a safety razor holder or handle having combined therewith a liquid soap container and means whereby the soap can be applied to the face and worked up into a lather.

To this end, the improved razor holder comprises a hollow shell or chamber having curved walls, and adapted to receive a flexible bag or sack of soap, said shell having at one side a soap discharge aperture provided with marginal flexible strips whereby the soap may be rubbed on the face, and having at the opposite side means for supporting a razor blade in operative position for shaving.

In order that the invention may be clearly understood, reference is had to the accompanying drawings, forming part of this specification, and in which:—

Figure 1 is an elevational view of my improved safety razor;

Figure 2 is a transverse sectional view thereof, partly in section, parts being in elevation;

Figures 3 and 4 are views similar to Figure 1, showing different adjustments of the razor blade;

Figure 5 is a section on line 5—5 of Figure 2;

Figure 6 is an enlarged sectional view of the lathering strips shown in Figure 2; and

Figure 7 is a perspective view of a liquid soap sack.

Like reference characters indicate like parts throughout the following specification and in the several views in the drawings in which 1 indicates my improved safety razor, which includes a handle 2, screw threaded to a shell or support 3, upon which the razor blade holder 4 is pivotally mounted. This razor blade holder includes a guard 5, and a clamp 6 between which the blade 7 is held. The guard member 5 may be angularly adjustable, and to this end is shown as pivoted at 8 to the member 3, and has attached thereto a spring lever 9, having a ball end 10 by means of which it may be manipulated and through means of which the member 5 may be held in adjusted position through the pro-

vision of recesses 11, 12 and 13 in the under surface 14 of the member 3, into which the ball 10 is adapted to drop and be frictionally held through the spring tension of the said lever 9. Through this arrangement the 55 razor blade holder may be shifted to and maintained in any one of three positions, such as shown in Figures 1, 3 and 4.

The member or shell 3 may be either cylindrical, or elliptical in cross section as shown 60 in Figure 2. It is preferably made of thin metal, formed in two halves or sections, hinged together at one side as indicated at 23. The handle 2 is secured to one of these sections, as at 22, while the other supports the 65 razor blade holder. This shell or container is adapted to receive a flexible sack or bag 15, preferably formed of soft rubber, and containing liquid soap. This sack has a filling opening or mouth 25, at one end, which is 70 suitably sealed at the factory, and is provided along one side with a series of teats 16, having small holes at their ends. When the sack is placed in the shell or container, the teats 16 project through an elongated opening at the side thereof, and are received between a pair of flexible lathering strips 17 and 18, arranged at the margins of such opening. As shown, these lathering strips are mounted on the shell, but it is obvious that 75 they can as well be secured directly to the sack 15, if desired. In any event, the strips enclose or house the ends of the teats, and project laterally beyond the same. The outer edges of the strips normally lie in contact 80 with each other as shown in Fig. 6, thus forming a seal to prevent drying out of the soap. At one end the halves of the shell are provided with co-operating pockets 26, 27, to receive the filling mouth of the sack 15, as 85 shown in Figure 5, while at the opposite end is a suitable catch 24, to hold the shell closed. The sack rests in the shell on a plate 21, secured to a rod 19, slidably mounted in the handle 2, and provided with an operating lug 90 or head 20, and it is obvious that when this plate is pressed against the sack, by pushing with the finger upon the head 20 of the rod 19, the plate will squeeze the bag 15, and force the liquid soap through the teats 16, 100

into the space between the strips 16 and 17, which form the lathering device, whereby when said lathering device is drawn back and forth upon the face of the user a lather may be readily worked up. Having properly lathered the face, the user may, by simply reversing the device, bring the razor blade into position for shaving.

The member 3 is preferably formed in two portions hingedly united at one side as shown at 23, and the two parts yieldably held in closed position by any suitable means, for instance by a spring catch conventionally shown at 24.

At one end the soap container 15 is formed with a small feed tube 25 adapted to be projected into small coacting recesses 26-27 in the confronting walls of the member 3, and held compressed thereby, to prevent leakage of the soap. When removed from the member 3, the tube 25 provides means for charging the bag 15 with its supply of soap.

Having described my invention that which I claim to be new and desire to procure by Letters Patent is:

1. A safety razor comprising a handle and a hollow shell, a liquid soap container within said shell, a razor blade holder mounted at one side of said shell, and a soap dispensing device at the other side of said shell.

2. A safety razor comprising a handle and a hollow cylindric shell, a liquid soap container within said shell, a razor blade holder mounted at one side of said shell, and a combined soap dispensing and lathering device at the other side of said shell.

3. A safety razor comprising a hollow shell formed in two sections hinged together, a soap container adapted to be received within said shell, means for discharging the soap as desired, a razor blade holder mounted on one of said sections, and a handle secured to the other of said sections.

4. In a self-lathering razor, a member comprising a hollow shell formed of a pair of hingedly connected sections and having a discharge opening formed partly in each section, a soap containing flexible sack received within said shell between said sections and having teats projecting through said opening, and means for compressing said sack to expel the soap from said teats.

5. In a self lathering razor, a shell having an elongated opening, a liquid soap containing flexible sack disposed within said shell, a pair of flexible lathering strips projecting from said opening and a plunger arranged to compress said sack to discharge soap therefrom between said strips.

6. In a self lathering razor, a shell having an elongated opening, a liquid soap containing flexible sack disposed within said shell, a pair of flexible lathering strips projecting from said opening, a series of teats projecting from said sack and lying between said

strips, and a plunger arranged to compress said sack to discharge soap from said teats.

7. A self-lathering razor comprising a hollow shell having an opening, a hollow handle to which said shell is secured, a liquid soap containing flexible sack within said shell and having a teat projecting through said opening, and a plunger having a head adapted to engage and compress said sack to discharge soap from said teat, and having a shank reciprocal within said hollow handle.

In testimony whereof I affix my signature.

LUTHER C. JOHNSTON.
